UNITED STATES PATENT OFFICE.

CLAUDE E. WAGNER AND BERT G. HOFER, OF LOS ANGELES, CALIFORNIA.

MARCELING IRON.

Application filed December 9, 1925. Serial No. 74,274.

This invention relates to improvements in curling or marceling irons.

An object of this invention is to provide an iron of this class which consists essentially of two clamping members with which are associated two handles, the handles being connected to their respective clamping members in such a manner that a small movement of the handles will produce a large movement of the clamping members, so that persons with small hands can easily spread and contract the handles only a small distance but at the same time will cause the clamping members to spread and contract a great distance, thus facilitating the spreading of the clamping members and aiding in wrapping hair upon the iron.

Another object of this invention is to provide an improved curling iron which is of cheap yet durable construction and which has a relatively small number of parts, which cannot easily get out of order, but if they should become damaged for any reason, they may be easily and quickly replaced.

With the foregoing and other objects in view which will be made manifest in the following detailed description and specifically pointed out in the appended claims, reference is had to the accompanying drawings for an illustrative embodiment of the invention, wherein:

Figure 1 is a side elevation of the improved curling iron, the clamping members being shown in closed position,

Fig. 2 is a view similar to Fig. 1, the clamping members being illustrated in open position,

Fig. 3 is a vertical section through the housing of the curling iron in the position shown in Fig. 1,

Fig. 4 is a similar view to Fig. 3, the clamping members being illustrated in open position, and

Fig. 5 is a vertical section taken substantially on the line 5—5 on Fig. 1.

Referring to the accompanying drawings wherein similar reference characters designate similar parts throughout, the improved curling or marceling iron consists of two clamping members 10 and 11. The member 10 is preferably cylindrical in form and is constructed of steel or equivalent material. The clamping member 11 is semi-cylindrical in form presenting a concaved interior surface substantially complementary to the convex surface presented by the clamping mem-

ber 10. The ends of both of the clamping members are preferably beveled off, as indicated at 12, although this construction is immaterial.

Provided upon the clamping member 11 is a housing having two side walls 13 and 14 which are connected by a top wall 15 and a bottom wall 16. The clamping member 10 extends into this housing and is pivoted or fulcrumed therein intermediate its ends as by a suitable screw 17 or the like. The end of the member 10 which is disposed within the housing is provided with a head 18 preferably having flat sides and presenting a cylindrical peripheral surface.

Rigid with the housing is a handle 19. A second handle 20 extends into the housing and is pivoted or fulcrumed therein as by a screw 21 or the like. The end of the handle 20 disposed within the housing is provided with a recess 22 which receives the head 18, thus providing a socket for the head. Preferably both of the handles 19 and 20 are shouldered and suitable grips 23 are rotatably mounted thereon between the shoulders. It will be readily understood, however, that these grips can be omitted or they may be provided on only one of the handles. Their purpose is to facilitate the turning of the curling iron in the hand, and some persons desire that both grips should be used which are rotatable. Others desire merely a single rotatable grip and still others do not care for rotatable grips at all.

It will be noted that the distance between the pivot screw 21 and the point of engagement between the member 10 and the handle 20 is greater than the distance between the point of engagement and the pivot pin 17. Therefore, by spreading the handles 19 and 20 only a slight distance, the clamping members 10 and 11 will be caused to spread a considerably greater distance, thus permitting a person with a small hand to open the clamping members wide very easily.

In operation the iron is heated and the hair can be wound upon the clamping member 10, after which the clamping members can be pressed together by the handles 19 and 20 and caused to clamp upon the hair. It will, of course, be appreciated that the iron is not restricted to this particular use, but may be used merely to clamp strands of hair between the heated clamping members, as in marceling.

It will be noted that as the rear end of

the housing is left open, it exposes a great deal of the metal of which the housing is formed to the air, thus radiating the heat from the clamping members, so that the 5 handles will not become warm.

It will readily be understood that the specific manner illustrated of connecting the handle 20 to the member 10 is immaterial. Obviously, other constructions can be used, 10 such as gear segments and the like.

From the above described construction it will be readily appreciated that the improved iron is very advantageous in that it can be used very efficiently by persons with small 15 hands. Furthermore, if the iron should become burned or otherwise damaged, any of the parts, such as the clamping member 10, the handle 20 or the member providing the clamping member 11 and the housing together 20 with the handle 19, can easily and quickly be replaced.

It will be understood that various changes may be made in the detail of construction without departing from the spirit or scope 25 of the invention as defined by the appended claims.

We claim:

1. A marceling iron comprising two clamping members, one member being rodlike in form and the other being in the form of an inverted channel disposed over the rodlike clamping member, a handle rigid with the inverted channel shaped clamping member, and a second handle disposed 30 beneath the first handle and pivotally connected thereto, said rodlike clamping member being pivotally connected to the inverted channel shaped clamping member and being operatively connected to the second handle, so that when the second handle is moved downwardly from beneath the first handle, the rodlike clamping member will be swung downwardly from beneath the inverted channel shaped clamping member.
- 45 2. A marceling iron comprising two clamping members, one being rodlike in

form and the other being in the form of an inverted channel disposed above and adapted to fit over the rodlike clamping member, a first handle, a tubular housing open at both ends rigidly connecting the first handle to the inverted channel shaped clamping member, and a second handle disposed beneath the first handle having one end extending into and pivoted within said housing, one end of the rodlike clamping member extending into and being pivoted within said housing, said rodlike clamping member being operatively connected to said second handle, whereby when the second handle is moved downwardly from beneath the first handle, the rodlike clamping member will be swung downwardly from beneath the inverted channel shaped clamping member.

3. A marceling iron comprising two 65 clamping members, one being rodlike in form and the other being in the form of an inverted channel disposed above and adapted to fit over the rodlike clamping member, a first handle, a tubular housing open at 70 both ends rigidly connecting the first handle to the inverted channel shaped clamping member, and a second handle disposed beneath the first handle having one end extending into and pivoted within said housing, one end of the rodlike clamping member extending into and being pivoted within said housing, said rodlike clamping member having a cylindrical head formed upon that 75 end which is disposed within the housing and which fits within a semi-cylindrical recess formed upon the end of the second handle, which is disposed within the housing, whereby when the second handle is moved downwardly from beneath the first handle, the rodlike clamping member will be swung downwardly from beneath the inverted channel shaped clamping member.

In testimony whereof we have signed our names to this specification.

CLAUDE E. WAGNER.
BERT G. HOFER.
